Burke, Fraser & Connell

UNITED STATES PATENT OFFICE.

JAMES WATSON, OF LONDON, ENGLAND.

BALING-PRESS.

SPECIFICATION forming part of Letters Patent No. 294,551, dated March 4, 1884.

Application filed January 8, 1884. (No model.) Patented in England April 28, 1883, No. 2,155.

To all whom it may concern:

Be it known that I, JAMES WATSON, of London, England, have invented certain new and useful Improvements in Baling-Presses, of 5 which the following is a specification.

My invention consists of improvements in baling-presses, and has special reference to presses in which the cotton, jute, or other material to be formed into a bale receives first a 10 preliminary pressure by one or more rams, and then a final or finishing pressure by one or more other rams.

In a former patent, dated August 28, 1883, No. 283,838, I described a press of the kind 15 above referred to, in which a preparatory ram and a finishing-ram are arranged in parallel planes, and in which a set of finishing-boxes is mounted to revolve around an axis over said rams and arranged to be brought successively 20 into coincidence therewith, and a set of preparatory boxes is also mounted to revolve around an axis below the finishing-boxes, and arranged to be brought into coincidence, successively, with the preparatory ram and a finishing-box, whereby the preparatory ram is 25 enabled to force the material from the preparatory box into the finishing-box, and whereby the latter box, with the partly-finished bale, may be swung round to the finishing-ram, 30 so that the final or finishing pressure can be given thereto. The finishing-boxes described in my said former patent are each composed 35 of two main doors forming the two sides of the box; of an inner end to which said doors are hinged; of an easing-door forming the outer end; of a top lashing-plate, and of a toothed sliding stop, which supports the bale as soon as the follower of the preparatory ram begins 40 to descend.

Now, the objects of my present invention are to simplify the construction of that part of the press into which the cotton or other material is forced from the preparatory boxes, to diminish the weight which has to be swung round 45 from the preparatory ram to the finishing-ram, and vice versa, and to construct the press so that, without increasing the number or the power of the finishing-rams, the outturn from the press is much increased.

My invention, with the above objects, consists, first, in hinging the main doors of the

upper boxes to a fixed support, so that they do not swing round with the partly-finished bale, and in rigidly fixing to the center piece (which, in the press described in my said former patent, forms the inner end of the revolving finishing-box) one end of a wrought-iron or steel frame to support the bottom of the partly-finished bale, this frame having a central opening of exactly the same dimensions 55 as the sectional internal area of the preparatory boxes; secondly, in constructing the press with two sets of preparatory boxes and preparatory rams, disposed, respectively, at the opposite sides of the finishing-rams, the finishing-rams being supplied with the partly-finished bales from the two preparatory portions 60 of the press alternately.

In the annexed drawings, Figure 1 is an elevation, and Fig. 2 a horizontal section, of a 70 press embodying my present improvements. Fig. 3 is a vertical section through one of the preparatory portions of the press.

a a are the finishing-rams; *b b'*, the two preparatory rams disposed, respectively, on the 75 two sides of the rams *a a*.

c c c' c' are the two sets of preparatory boxes. (There are two shown in each set, but this number may be varied.)

d d' are columns, around which the sets of 80 boxes *c c' c' c'* can be revolved.

e e e' e' are the main doors of the upper boxes. They are hinged to the columns *d d'*.

f f' are center pieces mounted, respectively, upon columns *g g'*, and forming the inner ends 85 of the upper boxes.

h h' are wrought-iron or steel frames rigidly fixed at one end to the pieces *f f'*. The openings *i i'* in these frames are of the same dimensions as the sectional internal area of the 90 boxes *c c'*.

k k' are top lashing-plates.

l l' are the end easing-doors.

m m' are locking-keys, which enter holes in the frames *h h'* and prevent the easing-doors 95 springing outward when the bale is being formed. The bottom parts of the doors *l l'* also catch into the frames *h h'* and support them against downward pressure, due to the expansion of the bale when held between the frame and the lashing-plate. As seen in Fig. 3, the width of the upper boxes—that is to 100

say, the distance between the two main doors when closed—is slightly greater than the width of the openings in the frames *h h'*.

The doors *e' e'*, at the left-hand side of the press, are seen fully open in Figs. 1 and 2, while the doors *e e*, at the right-hand side, are broken away in Fig. 1, and shown partly open in Fig. 2. These figures also show the finishing-rams in the position they occupy after having given the final or finishing pressure to a bale which has been brought from the preliminary ram at the left-hand side, and they show the preliminary ram and parts at the right-hand side in the positions they occupy when said ram has completed the preliminary pressure, and the main doors have been opened.

The action of the press (referring for the present only to the right-hand side) is as follows: The parts being in the positions seen in the figures, (except that the doors *e e* must be closed, and the ram *b* must be at the bottom of its stroke,) and the box *c* which is in line with the ram *b* being full of the cotton or material to be compressed, the ram rises into the position seen in Fig. 1, and in so doing it forces the cotton from the box *c* into the upper box. When the ram has reached this position, the doors *e e* are unlocked, either automatically by the rise of the ram (in a manner well understood) or by hand, and pushed back to the position seen in Fig. 2. The men may then commence lashing the bale, the ram meanwhile holding it up. The men pull the ropes or hoops partially tight, and in order to prevent the ends slipping they insert a wooden wedge into the rope-grooves of the top lashing-plate, *k*, above the rope or hoop ends, so as to press them against the bale; or the bale may be held on the top of the frame without any lashing at all, the lashing commencing only after the bale is in position over the finishing-rams. The ram *b* is then allowed to descend clear of the frame *h*, and the bale is partly held in position by friction against the parts which embrace it, and the ropes or hoops prevent it returning into the box. If the bale expands downward so far as the frame *h*, its edges cannot go past the top of this frame, as the opening therein is not so wide as the distance between the doors *e e* when closed, and the bale expands somewhat after the doors are opened. The ropes or hoops are now caught and held fast by the expansion of the bale pressing them against the top inside edge of the frame *h*.

The bale, as thus held in a sort of chamber or box without sides, is now swung round on the column *g* into position over the finishing-rams *a a*, and these rams rise to give the final pressure, the men, as the rams rise, continuing the lashing of the bale. In the meantime the other box *c*, full of material to be compressed, has been brought in line with the ram *b*, and the moment the bale is tumbled out of the press, and the follower of the rams *a a* falls clear of the frame *h*, this frame and the other parts which revolve therewith are swung back into line with the ram *b*, the doors *e e* are shut, and this ram rises to press another bale. The same actions take place at the left-hand side of the press, the movements and operations at the two sides being of course so timed that the bales are brought to the finishing-rams alternately, from the two preparatory portions of the press.

If desired, the sliding stops described in my said former patent may be fitted to the press, and made to pass either through the frames *h h'* or above them, to support the bales when the followers of the rams *b b'* descend; but I do not consider these stops necessary with the arrangement above described.

What I claim is—

1. The doors *e e*, hinged to a fixed piece, *d*, in combination with a frame, *h*, fixed at one end to a center piece, *f*, and with a lashing-plate, *k*, and easing-door *l*, said pieces *h*, *f*, *k*, and *l* being mounted to revolve, so as to be brought into coincidence at one time with a preparatory ram or rams, and at another time with a finishing ram or rams, substantially as and for the purpose set forth.

2. The combination, with the finishing ram or rams *a a*, of the two preparatory rams *b b'*, two sets of preparatory boxes, *c c' c' c*, two pairs of main doors, *e e' e' e'*, and two sets of revolving or swinging devices, *f h k l* and *f' h' k' l'*, for swinging the partly-finished bales from the preparatory rams to the finishing ram or rams, substantially as set forth.

In testimony whereof I have hereunto signed my names in the presence of two subscribing witnesses.

JAMES WATSON.
